TRIMMING ATTACHMENT FOR SEWING MACHINES

Joseph Galkin, New York, N. Y.

Application December 16, 1952, Serial No. 326,264

3 Claims. (Cl. 112—122)

1

This invention relates to trimming mechanism for sewing machines; and particularly to that type of trimming mechanism wherein a movable cutting blade passes up and down through the work support of the sewing machine, and by cooperation with a fixed blade substantially level with the work support, trims the fabric which is being seamed.

In such trimming mechanism as heretofore constructed, when operating on soft fabric, the trimmed selvage material cannot push the trimmed selvage material ahead of it and the machine gets clogged up and the selvage gets caught and packed behind the heel of the movable blade and makes the machine inoperative.

Instead of attempting to push the chips rearwardly over a flat horizontal work supporting base, this attachment guides the chips downwardly and forwardly of the machine.

This attachment comprises a chip guard or guide trough having a wall which extends slightly to the rear of the movable cutting blade and terminates in a downwardly and forwardly extending inclined guide wall which guides the selvage trimmings forwardly and so that the trimmed selvage material falls down at the front of the machine due to its weight.

This attachment relates particularly to sewing machines designed for attaching an elastic tape to woven fabrics such as the waistbands of bloomers to permit the waist portion to stretch to the required size.

In prior art it was necessary to fold the edge of the garment fabric. The stitching passed over the folded edge and covered the edge.

With the attachment herein disclosed, the waistband edge of the garment fabric is trimmed just prior to the stitching operation. The stitching passes over and conceals the trimmed but unfolded edge. The resulting seam is flat and of less thickness than the prior edge-folded seam.

This invention is particularly directed to an improved trimming attachment wherein the movable cutting blade is actuated from below the work supporting base of the sewing machine and the main object of this invention is to provide an arrangement of mechanism whereby the base is free of upstanding brackets and the operator can clearly see the materials being fed to the needles and this results in improved quality of workmanship.

Another object of this invention is to provide a movable chip guard fixed to a movable blade carrier and at the upper surface of a movable blade and movable up and down with the blade while slightly inside the fixed chip guard, the movable chip guard having an upright extension sloping forwardly and causing the chips to move forwardly and fall into the fixed chip guard.

2

which facilitates their sliding out from the machine.

This application is a continuation in part of my now abandoned patent application, Serial No. 33,114, filed June 15, 1948, and a continuation in part of my now abandoned patent application, Serial No. 57,950, filed November 2, 1948.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a fragmentary top plan view of a work supporting base of a sewing machine embodying the invention.

Figure 2 is a front elevation of a fragmentary portion of the work supporting base portion of the sewing machine shown in Figure 1.

Figure 3 is a fragmentary top plan view of the work supporting base shown in Figures 1 and 2, and including a modified and improved trimming mechanism.

Figure 4 is a front elevation of a fragmentary portion of the trimming mechanism shown in Figure 3.

Figure 5 is a cross-sectional view taken on line 5—5 in Figure 3, and showing nested chip guards.

Figure 6 is a view similar to Figure 5, without the chip guards.

Figure 7 is a cross-sectional view taken on line 7—7 in Figure 3 and showing a dual guard arrangement.

In the illustrated embodiment of the invention, shown in Figures 1 and 2, the numeral 10 indicates a work supporting base of a sewing machine, comprising a base plate 11, two spaced needles 12, and a presser-foot 13, resting on a needle plate 14 secured to the work supporting base 10.

Projecting through the needle-plate 14 is a work advancing feed-dog 15 having actuating mechanism (not shown) but which may be of the usual four-motion type of feeding mechanism.

The feed-dog 15 is opposed by the presser-foot 13 having its shank 16 suitably secured to the lower end of a presser-bar 17 vertically movable in the head of the sewing machine in the usual manner.

The needles 12 are secured in a needle-bar 18 vertically movable in the head of the sewing machine. Cooperating with the needles 12 below the work supporting base 10 is an oscillating looper (not shown). The looper thread interlocks with the needle threads to form two needle 60 interlock stitching.

3

A main shaft 20 is suitably journaled in the base portion of the machine and from which the stitch forming and feeding elements are driven.

The trimming mechanism comprises a cutting blade 21 fixed to the work supporting base 10 and which lies parallel to the line of stitching and with its cutting edge at the upper level of the work supporting base 10.

A cooperating movable cutting blade 22 is carried by a slotted head 23 at one end of a rod 24. The rod 24 is slidably mounted in spaced-apart bearing portions 25, 26 of a rocker arm 27. A coil spring 28 mounted on the rod 24 and compressed between a slidable collar 29 and the bearing 26, urges the movable blade 22 in yieldable cutting engagement with the fixed cutting blade 21. The collar 29 is bifurcated and engages the rocker arm 27 and prevents rotation of the rod 24.

The rocker arm 27 is fixed to a rod 30 rockably mounted in brackets 31, 32 fixed to the base plate 11. The rocker arm 27 is oscillated through a link 34 fixed to the rod 30 and through a strap arm 35 from an eccentric 36 at one end of the main shaft 20.

The movable cutting blade 22 is of arcuate form and its lower end or heel portion coacts with the fixed cutting blade 21 to trim the right-hand edge of fabric fed by the feed-dog 15 to the needles 12.

In order to positively clear the blades of the trimmed selvage and prevent clogging of the blades I provide a chip guard 37 having a vertical wall 38 extending slightly to the rear of the heel of the movable blade 22.

At the lower end of the vertical wall 38, the guard 37 extends forwardly and downwardly as defined by an inclined wall 40. The work supporting base 10 has a covered opening 41 and the presser-foot has a transverse opening 42 in front of the needles to permit the guard wall 38 to extend upwardly therethrough and terminate slightly above the work-supporting base 10. The lowermost edge of the chip guard 37 extends outwardly beyond the work supporting base 10 and delivers the trimmed selvage clear of the sewing machine. The guard 37 is fixed to the base plate 11 by screws 43.

Figures 3 to 7, inclusive, show a modified and improved trimming mechanism 50.

As shown in Figures 3 to 7, inclusive, the numeral 10 indicates a fragmentary portion of the work-supporting base of the sewing machine shown in Figures 1 and 2.

The sewing machine shown in Figures 3 to 7, inclusive, comprises the base plate 11, two spaced needles 12 and a presser-foot 13 resting on a needle-plate 14.

Projecting through the needle-plate 14 is the work advancing feed-dog 15 having actuating mechanism of the usual four-motion type.

The feed-dog 15 is opposed by the presser-foot 13 having its shank 16 secured to the lower end of the presser-bar 17 vertically movable in the head of the sewing machine in the usual manner.

The needles 12 are secured in the needle bar 18 and cooperate with an oscillating looper 19 to form two needle interlock stitching.

The main shaft 20 is journaled in the base portion 11 of the machine and drives the stitch forming and feeding elements.

The improved trimming mechanism 50 comprises a cutting blade 21 fixed to the work supporting base 10 and which lies parallel to the

4

line of stitching and with its cutting edge at the upper level of the work supporting base 10.

The improved trimming mechanism 50 comprises a carrier plate 51 positioned below the work supporting base 10 and a shaft carrying bracket 52 which is adjustable with the carrier plate. The bracket 52 has an elongated key-shaped extension 53 positioned parallel with the shaft 54. The carrier plate 51 has a keyway 55 into which the key-shaped extension 53 is slidably mounted. A screw 56 is threaded in a lug 57 which extends downwardly from the carrier plate 51. A screw 60 passes through an elongated slot 61 in the carrier plate 51 and is threaded into the extension 53. It is thus possible by means of the screws 56 and 60 to adjust the bracket and the blades in desired relation to the carrier plate so that the blades 21 and 62 are in pre-determined spaced-apart relation from the needles. This adjustment controls the width of the trimmed seam.

The cooperating movable cutting blade 62 is carried by a rocker arm or movable blade carrier 63 fixed to the shaft 54. The shaft 54 is rockably mounted in a bearing 65 extending from the bracket 52.

The rocker arm 63 is oscillated through a link 66 fixed to the shaft 54 and through a strap arm 67 from an eccentric 68 on the main shaft 20.

The movable blade 62 is substantially C-shaped, and at its upper portion it co-acts with the fixed cutting blade 21 to trim the right-hand edge of the fabric fed by the feed-dog 15 to the needles 12.

A coil spring 58 mounted on the shaft 54 and compressed between a thread nut 59 and the bearing 65 urges the movable blade 62 in yieldable cutting engagement with the fixed cutting blade 21.

In order to positively clear the blades 21 and 62 of the trimmed selvage and prevent clogging of the blades while maintaining a clear upper surface of the work supporting base 10, I provide a main chip guard 69 which is fixed to a supplemental portion 70 of the work supporting base 10 by screws 71. The chip guard 69 has a substantially vertical guard wall 72 extending slightly to the rear of the cutting blades.

The chip guard 69 has a forwardly and downwardly inclined wall 73 which terminates at the front face of the base 11. A supplementary guard plate or cover plate 75 is fixed in upright position to the base 11 by screws 76.

A further chip guard 77 is secured by a screw 74 to the movable blade carrier 63 and has an upright side wall 78 which is bent downwardly. The chip guard 77 has a vertical and forwardly curving guard wall 79 following the C-shape of the movable blade 62.

The work supporting base 10 has a through covered opening 80 and the presser-foot 13 has a transverse opening 82 in front of the needles to permit the guard walls 72 and 79 to extend upwardly therethrough and terminate slightly above the work-supporting base 10.

The lowermost portion of the chip guard 69 extends outwardly beyond the base plate 11 and delivers the trimmed selvage clear of the sewing machine.

As shown in Figures 4 and 5, it will be seen that by actuating the shaft 54 by a transverse link 66, that an unobstructed opening 85 is provided in the front portion of the base and in alignment with the main chip guard 69.

The trimmed selvage is thus constrained to move sideways through the transverse opening

82 in the presser-foot 13, downwardly over the upright wall 79 of the further chip guard 77 and then forwardly over the wall 73 of the main chip guard 69 and entirely clear of the forward face of the sewing machine base 11.

The arrangement disclosed makes possible continued operation of the sewing machine because the selvage or chips cannot reach the working parts inside the base 11 and are further kept away from the upper surface of the work supporting base 10 and automatically delivered outside the machine, which was not possible heretofore.

An important improvement of this modified attachment over attachments heretofore in use, is that the stationary blade 21 is integral with a 15 slideable bracket 52 carrying the shaft 54.

The result is that both blades may be moved simultaneously to the right of the needle to increase the amount of fabric left at one side of the 20 needles for strength, etc.

In accordance with the patent statutes I have described and illustrated the preferred embodiment of my invention, but it will be understood that various changes and modifications can be made therein without departing from the spirit of the invention as defined by the appended 25 claims.

I claim:

1. In a trimming attachment for a sewing machine having a needle, comprising a work supporting base, a presser-foot, a cutting blade fixed to said work supporting base, a cooperating movable cutting blade carried by a movable blade carrier and actuated from a horizontal shaft 35 rockably mounted directly below said work supporting base, a main chip guard fixed to said work supporting base and having a rearwardly and upwardly inclined wall terminating in a guard wall positioned slightly to the rear of said cutting blades and forming an unobstructed opening at the front portion of said base and to one side of said needle, a further chip guard fixed to said movable blade carrier and facing downwardly into said main chip guard and having a rear upright guard wall, said work supporting base having a portion removed providing a through opening to permit said vertical guard walls to extend upwardly above said work supporting base, said presser-foot having a transverse opening permitting said movable cutting blade to pass upwardly therethrough, and means for actuating said rock shaft from beneath said work supporting base to thereby leave said front opening unobstructed and in coaction with the 40 needle and with said main chip guard, whereby selvage trimmings from said cutting blades may move downwardly through said transverse opening in said foot, downwardly over said upright guard wall of said further chip guard and then forwardly over said inclined wall of said main chip guard and discharge entirely clear of the forward face of the 45 sewing machine base.

2. In a trimming attachment for a sewing machine having a needle, comprising a work supporting base, a presser-foot, a bracket slidably mounted below said work supporting base, a cutting blade fixed to said bracket, a co-operating movable cutting blade carried by a movable blade carrier and actuated from a horizontal shaft 50 rockably mounted directly below said work supporting base, a spring pressing against one end of said shaft and causing said fixed and movable cutting blades to be in tensioned cutting relation, a main chip guard fixed to said work 55 supporting base and having a rearwardly and upwardly inclined wall terminating in a guard wall positioned slightly to the rear of said cutting blades and forming an unobstructed opening at the front portion of said base and to one side of said needle, a further chip guard fixed to said movable blade carrier and facing into said main chip guard and having a rear upright guard wall, said work supporting base having a portion removed providing a through opening to permit said vertical guard walls to extend upwardly above said work supporting base, said presser-foot having a transverse opening permitting said movable cutting blade to pass upwardly therethrough, and means for actuating said rock shaft from beneath said work supporting base to thereby leave said front opening unobstructed in its 60 co-action with said needle and with said main chip guard, whereby selvage trimmings from said cutting blades may move downwardly through said transverse opening in said foot, downwardly over said upright guard wall of said further chip guard and then forwardly over said inclined wall of said main chip guard and discharge entirely clear of the forward face of said sewing machine base, said slideable bracket permitting both said blades to be jointly moved 65 sideways of said needle to vary the amount of fabric left at the trimmed edge of the fabric.

supporting base and having a rearwardly and upwardly inclined wall terminating in a guard wall positioned slightly to the rear of said cutting blades and forming an unobstructed opening at the front portion of said base and to one side of said needle, a further chip guard fixed to said movable blade carrier and facing into said main chip guard and having a rear upright guard wall, said work supporting base having a portion removed providing a through opening to permit said vertical guard walls to extend upwardly above said work supporting base, said presser-foot having a transverse opening permitting said movable cutting blade to pass upwardly therethrough, and means for actuating said rock shaft from beneath said work supporting base to thereby leave said front opening unobstructed in its co-action with said needle and with said main chip guard, whereby selvage trimmings from said cutting blades may move downwardly through said transverse opening in said foot, downwardly over said upright guard wall of said further chip guard and then forwardly over said inclined wall of said main chip guard and discharge entirely clear of the forward face of the 25 sewing machine base.

3. In a trimming attachment for a sewing machine having a needle, comprising a work supporting base, a presser-foot, a bracket slidably mounted below said work supporting base, a cutting blade fixed to said bracket, a co-operating movable cutting blade carried by a movable blade carrier and actuated from a horizontal shaft rockably mounted directly below said work supporting base, a spring pressing against one end of said shaft and causing said fixed and movable cutting blades to be in tensioned cutting relation, a main chip guard fixed to said work supporting base and having a rearwardly and upwardly inclined wall terminating in a guard wall positioned slightly to the rear of said cutting blades and forming an unobstructed opening at the front portion of said base and to one side of said needle, a further chip guard fixed to said movable blade carrier and facing into said main chip guard and having a rear upright guard wall, said work supporting base having a portion removed providing a through opening to permit said vertical guard walls to extend upwardly above said work supporting base, said presser-foot having a transverse opening permitting said movable cutting blade to pass upwardly therethrough, and means for actuating said rock shaft from beneath said work supporting base to thereby leave said front opening unobstructed in its co-action with said needle and with said main chip guard, whereby selvage trimmings from said cutting blades may move downwardly through said transverse opening in said foot, downwardly over said upright guard wall of said further chip guard and then forwardly over said inclined wall of said main chip guard and discharge entirely clear of the forward face of said sewing machine base, said slideable bracket permitting both said blades to be jointly moved sideways of said needle to vary the amount of fabric left at the trimmed edge of the fabric.

JOSEPH GALKIN.
